CONTAINER FOR ORGAN PERfusion

John P. Hall, South Pasadena, Calif., assignor to
American Hospital Supply Corporation

Filed Aug. 23, 1974, Ser. No. 500,128

Term of patent 14 years

Int. Cl. D24—01

U.S. Cl. D83—1 N

FIG. 1

FIG. 2

FIG. 3

FIG. 4

FIG. 5

FIG. 6

FIG. 7

FIG. 8

FIG. 9

FIG. 10

FIG. 1 is a perspective view of a container for organ perfusion showing my new design; with the cover partially opened;

FIG. 2 is a top plan view thereof;

FIG. 3 is a front elevational view thereof;

FIG. 4 is an end elevational view thereof;

FIG. 5 is an end elevational view thereof opposite to that shown in FIG. 4;

FIG. 6 is a bottom plan view thereof;

FIG. 7 is a rear elevational view thereof;

FIG. 8 is a perspective view thereof showing the cover in fully closed condition;

FIG. 9 is a top plan view of FIG. 8; and

FIG. 10 is an end elevational view of FIG. 8.

I claim:

The ornamental design for a container for organ perfusion, substantially as shown.
